UNITED STATES PATENT OFFICE.

HENRY C. MAUL, OF DETROIT, MICHIGAN, ASSIGNOR TO THE MICHIGAN STOVE COMPANY, OF DETROIT, MICHIGAN, A CORPORATION OF MICHIGAN.

GAS-BROILER.

1,091,943.

Specification of Letters Patent. Patented Mar. 31, 1914.

Application filed January 15, 1912. Serial No. 671,155.

To all whom it may concern:

Be it known that I, HENRY C. MAUL, a citizen of the United States, residing at Detroit, in the county of Wayne, State of Michigan, have invented certain new and useful Improvements in Gas-Broilers; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to gas broilers, and consists in the construction and operative association of parts hereinafter more fully set forth and claimed.

The object of the invention is to provide 20 in a gas broiler a broiling rack which may at all times be held in a horizontal plane, and which may be projected forwardly when desired, or raised and lowered with respect to the burner flame, provision being made 25 for manually manipulating the rack and for affording a counterpoise therefor so that the movement of the rack will be steady at all points in its travel.

The above object is attained by the construction illustrated in the accompanying drawings; in which:—

Figure 1 is a perspective view of a gas broiler embodying my invention, the legs thereof being broken away. Fig. 2 is a fragmentary view in vertical section through the movable frame which carries the broiler rack, and the burners which supply the flame for broiling. Fig. 3 is a vertical transverse section as on line 3—3 of Fig. 2. Fig. 4 is a fragmentary view in elevation showing the toothed circle bar with which the detent on the actuating lever is adapted to engage to lock the broiling rack at any point of adjustment. Fig. 5 is a sectional view as on line 5—5 of Fig. 6. Fig. 6 is a fragmentary view in section through the slidable handle of the actuating lever, the detent or pawl thereon, and the circle bar which co-operates with the pawl or detent to 50 lock the lever in adjustment. Fig. 7 is a vertical transverse section through the rear portion of the frame which carries the broiling rack, as on line 7—7 of Fig. 2.

Referring to the characters of reference, 1 55 designates a gas broiler of the type having

an upper oven 2, below the bottom of which are the transverse gas burners 3 which supply the heat for said oven and also afford the required flame for broiling. Below said burners is a broiling rack 4, shown more clearly in Fig. 1, upon which articles to be broiled are placed. This rack is supported to slide in the horizontally extending channel bars 5 located at the sides of the broiler. Each of the channel bars 5 is provided at 60 its ends with the projecting ears 6. The upper ends of the swinging arms 7 and 8 are pivoted at 9 to the ears 6 at the forward and rear ends respectively of said channel bars. Said arms are arranged in pairs, the 70 front pair 7 being connected by a cross bar 10 which is journaled in the broiler frame near the front thereof, and the rear pair 8 being connected by a cross bar 11 which is journaled in the frame at the rear. The 75 arms of each pair being connected by their respective cross bars, and the pairs of arms being connected by the channel bars 5, a frame is afforded which will swing upon the pivots of said arms 7 and 8, and maintain 80 the rack 4 carried in the channel bars of said frame always in a horizontal position as said frame swings.

To provide for manipulating the swinging frame which carries the broiling rack, a 85 lever 12 is connected to the projecting end 13 (see Fig. 3) of the journaled or pivotally mounted cross bar 10 of the arms 7 of said frame, whereby as said lever is swung in the arc of a circle movement is imparted to 90 the arms of the rack frame, causing the broiler rack to be carried outwardly and downwardly to the dotted position shown in Fig. 2 as said lever is swung forwardly, and to the position shown by solid lines in 95 said figure when said lever is returned to the normal position.

To afford a counterpoise for the swinging frame and rack, an arm 14 is caused to project downwardly and rearwardly from the 100 cross-bar 10, and a weight 15 is mounted on the free end thereof which serves to balance the weight of the broiler rack and frame, whereby said parts are caused to move evenly and smoothly when manipulated.

For the purpose of securing the swinging frame at any point of adjustment a toothed circle bar 16 is employed which is fastened to the side of the broiler adjacent the lever 12, and said lever is pro- 105 110

vided at its upper end with a vertically 60
slidable handle 17 having a recess 18 in its
upper end which receives a head 19 at the
upper end of said lever, whereby said han-
dle while rendered capable of vertical move-
ment on said lever cannot be withdrawn
therefrom. Formed integral with the lower
end of the slidable handle are the extend-
ing curved fingers 20, having at their termin-
als projecting detents 21 adapted to enter
between the teeth of the rack or circle bar
16, as illustrated by dotted lines in Fig. 5.
On each of said fingers is a projecting flange
22 adapted to strike upon the upper ends
of said teeth when the detents are placed
in engagement therewith to prevent said de-
tents wedging therein. The arrangement is
such that by sliding the handle upwardly
on the lever 12, as shown by dotted lines in
Fig. 6, the detents are carried free from
the teeth of the circle bar, enabling said le-
ver to be swung in either direction to effect
such an adjustment of the broiling rack as
may be desired, when upon releasing said
handle it will slide downwardly upon the
lever 12 and carry the detents thereof again
into engagement with the teeth of the circle
bar and lock the lever against movement.
In actuating the frame of the broiler rack
30 the handle 17 is grasped by the operator
and raised so as to free the detents thereof
from the teeth of the rack or circle bar,
when the lever 12 will be free to swing upon
its fulcrum.
35 When the swinging frame which carries
the broiler rack is actuated through the me-
dium of the lever 12 the rack carried by
said frame is normally projected forwardly
as said frame swings downwardly to the po-
sition shown by dotted lines in Fig. 2, in
which position the meat or other article
to be broiled may readily be placed upon
the rack, when, by a return movement of
said lever, said frame may be swung up-
wardly to carry the rack in proximity to
the flame of the burners. Should it be de-
sired to lower the broiler rack without car-
rying it forwardly from under the burners
the frame may be swung forwardly and
50 downwardly through the medium of the
lever 12 and the rack at the same time
shoved rearwardly in the channels of the
side bars 5, the effect of said combined
movement being to lower the broiler rack
55 with respect to the burner flame without
carrying it forwardly away from the heat
thereof, said rack remaining at all times in
a horizontal position. By this arrangement
the rack may be raised and lowered in a

substantially perpendicular plane, enabling 60
the distance between the broiling rack and
the flame to be varied within certain limits
without carrying said rack forwardly to
such an extent as to remove it from under
the burners.

Having thus fully set forth my invention,
what I claim as new and desire to secure by
Letters Patent, is:—

1. A gas broiler comprising a burner, a
rack frame below the burner mounted to 70
swing, a broiling rack carried at the top of
the swinging frame to slide therein, said
rack being at all times supported in a hori-
zontal plane, and a lever exterior to the
broiler connected with the rack frame for 75
manipulating it.

2. In a broiler, a rack frame comprising
pivoted arms, slide bars pivoted to the up-
per ends of said arms, a broiling rack slid-
ably carried on said slide bars and main-
tained thereon in a horizontal plane when
said frame swings, a lever for manipulat-
ing the rack frame, and a counterpoise for
said rack frame connected therewith.

3. In a broiler, a swinging rack frame 85
comprising pivotal supports, a broiling rack
mounted in said frame to swing therewith
and slide therein, a lever exterior to the
broiler connected to the pivotal member of
said supports for manipulating said swing-
ing frame, and means for locking said lever
at any point of adjustment.

4. In a broiler, a rack frame mounted to
swing, a broiler rack support pivoted to
said frame, and a broiling rack mounted to 95
slide forth and back in said pivoted sup-
port.

5. In a broiler, a rack frame pivoted to
swing, a broiling rack carried by said frame
in a horizontal plane, a lever for actuating 100
said frame, a toothed circle bar, a handle
slidable upon the end of said lever, said
handle carrying a detent adapted to en-
gage said circle bar to lock the lever against
movement, and means for preventing the 105
jamming of the detent between the teeth
of said circle bar.

6. In a broiler, a rack frame, a manipu-
lating lever for the rack frame, a locking
handle mounted on said lever to slide ver-
tically, and a stop upon said lever to pre-
vent said handle being lifted too far.

In testimony whereof, I sign this speci-
fication in the presence of two witnesses.

HENRY C. MAUL.
